DESIGN FOR A FASTENER PRONG RING

Thomas F. Slater, Waterbury, Conn., assignor
to Scovill Manufacturing Company, Water-
bury, Conn., a corporation of Connecticut

Application March 20, 1940, Serial No. 91,083

Term of patent 7 years

To all whom it may concern:

Be it known that I, Thomas F. Slater, a citizen
of the United States, residing at Waterbury,
county of New Haven, State of Connecticut,
have invented a new, original, and ornamental
Design for Fastener Prong Rings, of which the
following is a specification, reference being had
to the accompanying drawing, forming part
thereof.

Fig. 1 is a top view of a fastener prong ring
embodying my new design, and

Fig. 2 is a front elevation thereof.

I claim:

The ornamental design for a fastener prong
ring, substantially as shown.

THOMAS F. SLATER.
